MIMEOGRAPH

Fred Erikson, Brooklyn, N. Y., assignor of one-half
to Albert Lakofsky, New York, N. Y.

Application February 24, 1940, Serial No. 320,551

3 Claims. (Cl. 101—116)

This invention relates to mimeographs or similar reproducing or printing devices, and particularly to that type in which a stencil-carrying roller is employed.

5 In mimeograph machines of the rotary type, the roller upon which the stencil is mounted is usually journaled in fixed supports and the sheet to be imprinted is fed beneath the roller which is rotated by means of a handle in the form of a crank or by similar manually operated means. 10 In a structure of such type, the roller is of relatively large diameter; its supporting frame, bed plate, crank and other elements are large and weighty and the device as a whole is expensive. 15 The primary object of the present invention is to provide a small, compact and portable type of mimeograph particularly adapted for use in printing upon post cards, notices, or other relatively small sheets; which will be operated by a 20 supporting handle or yoke in which the roller is mounted, and by which the roller is rotated while held in frictional contact with the article to be printed.

Another object of the invention is to provide, 25 in a small, portable mimeograph device of the character described, means by which the roller, moving from an initial position or point of beginning, will, by a single stroke across a sheet of paper or a post card, imprint thereon the indicia borne by the stencil that is carried by the roller. 30 The invention also contemplates the provision of means by which the roller is automatically restored to its initial position before the beginning of the stroke when it is raised from the 35 surface of the sheet.

The invention additionally contemplates the provision of a simple means for changing stencils; of a readily demountable means for rotatively supporting the roller, and other elements 40 hereinafter described and more particularly pointed out in the claims appended hereto.

In the accompanying drawing, forming a part hereof, Fig. 1 is a side elevation of a mimeograph or reproducing device made in accordance with 45 the invention; Fig. 2 is a sectional view through the same; Fig. 3 is a plan view of the device, with parts broken away and other parts in section to disclose construction; Fig. 4 is a view of the rods which hold the ends of the stencil on 50 the roller, and Fig. 5 is a sectional view on the line 5—5 of Fig. 4, looking in the direction of the arrows.

With reference to the structure as disclosed in Fig. 1, 1 indicates the body of the roller which 55 is of cylindrical formation and is of foraminous

construction, so that the ink applied through the openings in the roller will penetrate therethrough and saturate the padding 2 secured around the peripheral surface of the roller.

Removably secured on top of the inked pad 2 and extending around the roller is the stencil sheet 3 which has reinforced or tabbed ends 4 that are inserted through slots 5 formed in rods 6, each of which receives one end of the stencil sheet. The rods 6 are held between ears 7 and 8, 10 one of these ears being formed on and projecting from a spider 9 forming one end of the roller 1, the other ear being provided on a similar spider 10 forming an opposite end of the roller. Screws 11 are threaded into the ends of the rods 6 and by loosening these screws slightly, the rods may be turned to enable the tab portions 4 of the stencil sheet 3 to be wound up on the rods for the requisite amount to hold the stencil sheet 15 taut and smooth around the periphery of the roller. To prevent inadvertent rotation of the rods 6 and the resultant loosening of the stencil sheet, springs 12, secured by rivets 13 to the roller, exert resilient pressure against the rods 20 and hold the same in any set position of adjustment. 25

The roller 1 is rotatively mounted upon an axle or spindle 14 which is secured in the arms of a yoke 15 on which is formed or otherwise provided, the handle 16. The spindle may be secured in the yoke by means of the set screw 17 or by any other suitable fastening means. 30

Projecting laterally from the outer face of the spider 9 is a stud 18 constituting a stop which limits rotative movement of the roller 1 in a 35 counter-clockwise direction, as viewed in Fig. 2, by impingement against a flat spring 19, secured to and projecting from one of the arms of the yoke 15. Secured to the other arm of the yoke by the screw 20, is a torsional spring 21 which 40 is curled around and secured to a hub 22 formed on or attached to the spider 10.

From the foregoing, the operation of the device will be readily understood. A stencil sheet 3 is prepared in the conventional way and secured on 45 the roller 1 by having its ends attached to the rods 6 which are adjusted to draw the stencil sheet smoothly around the roller. The ink, applied through the perforated roller saturates the padding 2 in the conventional manner. The 50 sheet, post-card or other element to be imprinted, shown at 23 in Fig. 1, is placed upon a flat surface and the device is held by the handle 16 while the roller, having its stop pin 18 disposed uppermost, is held on the surface of the 55

sheet 23 at one end thereof. The device is now moved in the direction of the arrow 24 (Fig. 1) and the roller is caused to rotate in the direction of arrow 25 because of its frictional contact with the face of the sheet being imprinted. When the device has reached the position shown in dotted lines in Fig. 1 the roller has been rotated for nearly a complete revolution, or at least sufficiently to enable the imprint from the stencil to be applied to the sheet 23. While this is taking place, the torsional spring 21 is being wound up so that when the roller is raised from the surface of the sheet 23 at the end of the printing stroke, the spring immediately rotates it in a direction opposite to that of arrow 25, thus restoring it to its initial position, or that which it occupied at the beginning of the printing stroke. The stop pin 18, impinging against the spring 19 limits the rotative movement of the roller under the impulse of the torsional spring 21 and normally retains the roller at the point of beginning.

It will be clear that with the small compact and portable mimeograph device disclosed, small sheets, postcards, notices or the like may be one after another placed under the roller which is moved across the sheet and with a single stroke makes the imprint thereon. The stencils may be readily changed; the device may be easily inked and the devices possess all of the facilities of the larger, more complicated and more expensive types of mimeographs.

I have herein shown the device in illustrative form, so that it will be obvious that various modifications may be made and refinements may be added to the same. For example, the spring 21, stop 18, spring 19 and other elements may be enclosed or housed in either casings provided on the yoke or else on the ends of the roller. Other modifications in the device may be readily made without departing from the spirit of the invention.

What I claim is:

1. A device of the character described comprising, a mimeograph roller, a handle in which the roller is journalled and by which the roller is manually held in frictional contact with a sheet and rotated across the face of the same, rods extending across the roller, a stencil sheet extending around the roller and having its ends attached to said rods, means for rotatively adjusting the rods to draw the sheet smoothly around the roller, a spring and a resilient stop

consisting of a flat spring for holding the roller in a predetermined position, said spring permitting rotative movement of the roller in one direction across the sheet to be imprinted and acting, when the roller is raised from the surface of the sheet at the end of its stroke across the sheet, to return the roller to the initial position of said roller against the resilient stop prior to its movement across the sheet. 5

2. A device of the character described comprising, a mimeograph roller provided with end plates, an axle extending through said end plates, a yoke in which said axle is mounted, said yoke being provided with a handle by which the roller is manually held in frictional contact with a sheet and rotated across the face of the same, a stencil sheet extending around the roller, a torsional spring having one end attached to the yoke, said spring extending spirally around the axle and having its other end attached to one of the end plates on the roller, a stop member on one of said end plates, a resilient stop element on the yoke against which the stop member is normally held by the spring, said resilient stop element consisting of a flat spring having a free end projecting away from the yoke, said spring permitting rotative movement of the roller in one direction across the sheet to be imprinted and acting when the roller is raised from the sheet to restore the roller to the position where the stop member is located in resilient contact with the stop element. 20 25

3. A device of the character described comprising, a mimeograph roller, a stencil removably held on said roller, a yoke in which the roller is rotatably mounted, a handle on the yoke, a spring for resiliently urging the roller in one direction and holding it in a predetermined position, a projection on the roller, a resilient stop on the yoke against which the projection is normally held by the spring, said stop consisting of a leaf spring secured adjacent one end to the yoke and having a free end standing away from the yoke and adjacent to which the projection contacts which resilient stop permits a limited amount of movement in the same direction as the impulse of the spring whereby a manual effort to rotate the roller across a sheet to be imprinted will be resiliently resisted by the projection operative against the resilient stop. 30 35 40 45 50
